UNITED STATES PATENT OFFICE.

OTTO R. BERGER, OF CLEVELAND, OHIO.

MOLDER'S FLASK.

1,149,328.

Specification of Letters Patent.

Patented Aug. 10, 1915.

Application filed January 2, 1914. Serial No. 809,839.

To all whom it may concern:

Be it known that I, OTTO R. BERGER, a subject of the Emperor of Germany, residing at Cleveland, in the county of Cuyahoga and State of Ohio, have invented certain new and useful Improvements in Molders' Flasks, of which the following is a specification.

This invention relates to flasks which are constructed of separable side and end members so that flasks may be made up for any desired size of casting without having a separate flask for each size.

The principal object of the invention is to provide a flask of this kind with a removable extension of similar separable construction, all of the parts of which may be readily assembled and taken apart.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings, Figure 1 illustrates the drag and cope of a flask to which extensions are secured at the top and bottom, parts being broken away to show a sectional elevation and a part of the lower extension being omitted. Fig. 2 is a plan view of the same with parts broken away to show the sectional construction at the corners, and Fig. 3 is a detail view showing the engaging means at the corners.

Both the drag and cope of this flask are formed with separable side members 5 and end members 6, all of the members having extremities beveled at 45 degrees, and with lugs 7 adapted to abut with each other, the lugs being provided with slots 8 which register. In the slot of the projection 7 of the side member 5 an alining block 9 is mounted on a pivot pin 10, the block being long enough to engage in the alined slot 8 of the lug of the adjacent end piece 6 which is to be connected to the side. Secured to the block 9 is a threaded pin 11 upon which is mounted an adjustable winged nut 13.

To assist in alining the side and end members 5 and 6 one of them is provided with perforations 14 at the ends and the other member is provided with a lug 15 and a pro-

jecting pin 16 which is adapted to enter the perforation 14 of the other member. The perforated member slips readily in position over the pins 16 of the member, the slots 8 of the adjacent side and end members are then in perfect alinement and the alining block 9 is rotated about its pivot point in one member to engage in the slot of the other member, and the winged nut is threaded upon the pin 11 to hold the adjacent members firmly in position.

In order to properly aline the drag and the cope with respect to each other the drag is formed with a projection 17 in which is mounted an alining pin 18, and the cope is formed with a corresponding perforated projection 19 with a slot 20 in the outer face thereof to engage the alining pin 18, the slot in the outer face being for the purpose of preventing the clogging of sand or other material in the hole for the pin. The end pieces are provided with projections 21 by means of which the drag and cope can be raised or separated from each other.

The members which form the sides and ends of the flask are preferably concave on the inside or with the opposite inside edges inclined inward to a slight degree. This inclination serves to hold the molder's sand more firmly in the drag or cope, and also serves the purpose of holding an extension for either the drag or cope firmly but releasably in position. This extension, which may be secured either at the top of the cope or bottom of the drag, comprises separable side members 22 and end members 23 with beveled extremities and fastening devices similar to the sides and ends of the drag and cope but not necessarily with the alining pins and perforations of the drag and cope members. The edges of the side members 22 and end members 23 are formed with an off-set angular portion 24 which is adapted to engage inside of the edge of the side and end members of the drag or cope, the outer faces of the off-set portion being at an angle complementary to the angle of inclination of the inner face of the member to which they are applied. In practice it is found that an angle of 9 degrees is sufficient. These angular off-set portions terminate short of the ends of the side and end members of the extension so that they do not interfere with the alining pins and perforations of the drag or cope, as shown in Fig. 1.

In order to place the extension in position on the drag or the cope the corresponding members of the extension may be assembled at the same time with the members of the drag or cope, or the extension may be applied to the flask after the flask is already assembled. In case the flask is already assembled the separate members of the extension are placed with the angular offset portion over the respective members of the part of the flask to which they are applied and when two adjacent members are in position they may be secured together at the corners, the last piece sliding easily into position in the same manner for the reason that no alining pins and perforations are provided in connection with the members of the extension. When the extension is in position the extremities are locked together and the extension is held firmly in position by means of the angular offset extensions 24 so that the depth of the flask is increased the amount of the extension. The engagement of the extension 24 is sufficient to prevent the disengagement of the extension from the part of the flask to which it is applied, even though that part is lifted from the extension and there is no tendency for the parts to become separated.

One of the great advantages of this construction is that by having a few sides and end members of different lengths a great many different sizes of flasks can be obtained by simply using the different lengths of sides and ends in pairs interchangeably.

What I claim is:

1. In a molder's flask, the combination with separable side members and separable end members, of slotted lugs at an angle to the members at their extremities and with the slots open from the outside and an alining block pivoted in the slot of the extremity of one member and adapted to engage the edges of the slot in the lug of the adjacent member for alining the two members with respect to each other.
2. In a molder's flask, the combination with separable side members and end members, of slotted lugs open from the outside at the extremities of the members with beveled edges so that the sides of the lugs abut when the extremities of adjacent members are at right angles to each other, and means pivoted in the slot of one of the members and adapted to engage the sides of the slot of the abutting member for alining them laterally with respect to each other and for binding them releasably together.
3. In a molder's flask, the combination with separable side members and end members having beveled extremities with abutting slotted lugs at an angle to the members, and an alining block pivotally mounted in the slot of one member and adapted to engage in the slot of the other member for alin-

ing both of the members, and fastening means in connection with the alining block for holding the members releasably together.

4. In a molder's flask, the combination with side members and end members with corresponding beveled extremities, slotted projections at an angle to the members at the ends of the members, an alining block pivotally mounted in one of the members and adapted to engage the sides of the slot of the other member, and a fastening device comprising a threaded pin projecting from the alining block and a nut adjustable on the pin to engage the said other member to hold it in position with respect to the first named member.

5. In a molder's flask, the combination with separable side members and end members, of means for alining the said members with respect to each other, and means embodying slotted lugs at the ends of the members with the slots disposed at an angle to the members, the slots being side by side and registering when the members are at right angles and the slots being open from the outside of the flask.

6. In a molder's flask, the combination with separable side members and end members, of means for alining the members with respect to each other at their ends, means for binding the members releasably together at the ends, said means comprising slotted projections at an angle to the members, an additional alining member in connection with the projection of one of the members adapted to engage the sides of the slot of the other member, and means in connection with the additional alining member for binding the side and end members releasably together at their extremity.

7. In a molder's flask, the combination with separable side members and end members, of means for alining them with respect to each other at their extremities, and additional means for alining them at their extremities embodying open slots and a member pivoted in the slot of one member to engage the sides of the slot of the other member for binding the members releasably together.

8. In a molder's flask, the combination with separable side members and end members having beveled extremities, of alining pins at the extremities of one pair of members, the other pair of members being formed with alining perforations to engage the pins, slotted projections at the extremities of the member adapted to register with each other, the slot being substantially at the same angle to both of the adjacent members, an alining block pivotally mounted in the slot of one member and adapted to engage the slot of the other member and to assist in alining it with the first member, a threaded pin in connection with the block, and a winged nut

adjustable on the threaded pin to bind the members releasably together at the extremities.

9. The combination with a molder's flask, 5 of an extension therefor comprising separable pieces adapted to engage the inside edge of the flask, and means to bind the separable pieces together thereby locking the extension in place on the flask.

10 10. The combination with a molder's flask, of a removable extension therefor comprising members formed with angular extensions adapted to engage inside of the flask, and means releasably to bind the separable 15 members together at their extremities thereby locking the projections of the extension in engagement with the flask.

11. The combination with a molder's flask, the inner edge of which is inclined inwardly, 20 of an extension therefor comprising separable members with an angular extension adapted to engage the inner face of the flask at the edge thereof, and means to bind the separable members of the extension releas- 25 ably together.

12. In a molder's flask, an extension comprising separable side and end members corresponding in length to the sides and ends of the flask, an angular projection of the 30 side and end members adapted to engage the side and end members of the flask, lugs at the extremities of the members of the extension with alined slots therein, and releasable fastening devices adjustable in the 35 slots for binding the extension members releasably together at the extremities.

13. The combination with a molder's flask having walls beveled inwardly at the edges, and an extension therefor comprised of separable members with an off-set projection 40 inclined outwardly and adapted to engage inside of the edges of the flask, and means to bind the separable members of the extension together whereby they are held in 45 fixed position with respect to the flask.

14. The combination with a molder's flask, of edges inclined inwardly, of an extension therefor comprising separable side members and end members, the separable side and 50 end members having offset angular projections terminating short of the ends of the

members and adapted to engage the inner edge of the flask, and means to secure separable members of the extension together at their extremities and to bind the extension in place on the flask. 55

15. In a molder's flask, the combination with separable side members and end members with the edges of the members inclined inwardly, one pair of members being formed with alining perforations, alining pins in connection with the other pair of members adapted to engage the said perforations adjacent the extremities thereof, slotted lugs in connection with the members at their extremities, blocks pivotally mounted in the slot in one pair of members and adapted to engage the slot of the other pair to form an additional alining means, a threaded pin in connection with the block and a thumb screw adjustable on the pin to bind the block in the slot and to hold the members together, an extension comprising separable side members and end members with an angular offset extension less in length than 75 the said members adapted to engage the inside face of the edge of the flask and to clear the alining pins at the extremities, and means to secure the members of the extension together at the corners and to bind the extension in position with respect to the flask. 70

16. In a molder's flask, the combination with separate side members and end members having alining slots at the ends extending at the same angle to each member, one of the members at each junction being provided with alining pins and the other with alining perforations corresponding thereto and an alining block mounted in the slot of 80 one member at each junction movable to engage in the slot of the other member at the junction, and means to bind the block in position in the slots of the adjacent members. 85

In testimony whereof I have signed my name to this specification, in the presence of two subscribing witnesses, on this 23rd day of December A. D. 1913. 95
